UNITED STATES PATENT OFFICE.

CHRISTIAN H. SALZMAN, OF CHICAGO, ILLINOIS.

GRAIN-BINDER.

SPECIFICATION forming part of Letters Patent No. 403,385, dated May 14, 1889.

Application filed June 19, 1886. Serial No. 205,668. (No model.)

To all whom it may concern:

Be it known that I, CHRISTIAN H. SALZMAN, residing at Chicago, in the county of Cook and State of Illinois, and a citizen of the 5 United States, have invented certain new and useful Improvements in Grain-Binders, of which the following is a full description, reference being had to the accompanying drawings, in which—

10 Figure 1 is a side elevation, with the breast-plate partly broken away. Fig. 2 is a plan view looking from the front; Fig. 3, a vertical section on line $\alpha\alpha$ of Fig. 4; Fig. 4, a plan view looking from the front, showing the 15 parts in their changed relation to each other from that shown in Fig. 2; Fig. 5, a detail of the disk-frame; Fig. 6, a front view, with part of the supporting-frames and knife-arm broken away; Fig. 7, a detail showing the 20 cam for operating the knife-arm. Fig. 8 is a detail view of the knotter.

The object of this invention is to simplify 25 the construction of a self-binding harvesting-machine knotter mechanism, to make its operation easier, and to improve its action by relieving it from sudden strain or jerks; and its nature consists in the several improvements hereinafter described and claimed as new.

30 In the drawings, A indicates the breast-plate; A', needle-slot through the breast-plate; B, discharge-board; C C', braces; D D', knotter stand or frame; E, brace; F, knotter cam-wheel; F', its hub; G, gear-teeth 35 for operating the pinion; H H', cam-wheel and cam-groove for operating the knife-arm; I I', discharge-arms; J K, cam on cam-wheel F; L L' M N, knife-arm; O, knotter-bill; P, disk-frame; Q, disk; R, rocker-arm; S S', disk- 40 spring or cord-holder; T, knotter-driving or power shaft; a, knife-arm pivot; b, anti-friction roller on knife-arm L; c, notch or opening in knife-arm for the passage of the knotter-bill; d, cord-passage through knife-arm; 45 e, projection or shoulder for attaching a spring to the knife-arm; f, spring; g, pin for moving the hinged jaw of the knotter-bill; h, knotter-bill pinion; i, inner flange on wheel F; i', flattened space on knotter-pinion; j j', bearings 50 on the knotter-frame for supporting the knotter-bill; k, anti-friction-wheel on the outer end of the hinged jaw of the knotter-bill; l,

knife; m, projection on knotter-stand co-operating with the knife; n, depressions, and o ridge or scroll tooth on the wheel F for operating the disk Q. 55

The breast-plate A, with its needle-slot A', is made in the usual form and provided with the extension or board B, to insure the discharge of the bound bundle in the ordinary 60 manner.

The knotter stand or frame D is made as shown. It is provided with the bearings D' D'' for supporting the knotter-shaft, and also with the bearings j j' for the shaft of the 65 knotter-pinion h. This knotter-stand is of less than the usual height, and, as will be seen, the knot-tying and cord-severing devices are brought nearer to the breast-plate than heretofore, and by the arrangement of the 70 parts I am enabled to bring the knife-arm through the breast-plate, so as to tie the knot nearer to the bundle than it has heretofore been tied, and by the construction and arrangement of parts shown I obtain a saving 75 in binding-cord, and as the knot is made nearer to the bundle it has less expansion after being bound than has been heretofore obtained.

In the cutting away of the breast-plate to 80 afford space for the cutting devices, the breast-plate differs from the ordinary construction. The knife-arm is pivoted to the knotter-stand at a, from which point the arm projects downward with a side arm, L', extending out to 85 the cam H, which is provided with an anti-friction roller at its outer end. At or near its lower end a notch, c, is provided, through which the point of the knotter-bill passes when it is rotated, and by the use of this 90 notch I am enabled to bring the parts closer together and improve the compactness of the device. This knife-arm is provided with an extension, M, which acts as a cord-guide and insures the entry of the cord into or through 95 the passage d. The knife-arm is provided also with an upward projection, N, in rear of the knotter, to which the cord-knife l is attached.

There is sufficient space between the projections M and N for the rotation of the knotter-bill when forming the knot, and the cutter l, by reason of its inclined form, severs the cord against the shoulder or border m of 100

the passage through the knotter-stand D. The knotter-stand may be provided at the point m with a detachable plate for renewal when worn, if desired. The border or edge 5 will, however, form a sufficient shoulder to enable the knife l to sever the binding-cord with ease and certainty. The knife-arm L is also provided with a shoulder or projection, e, to which the spring f is attached. The inner end of this spring bears upon the pin g, which passes through the knotter-pinion and closes the movable jaw of the knotter-bill. This pin is common in this class of knotters, as is also the anti-friction wheel k at the 15 outer end of the jaw, which presses or travels against the shoulder j and holds the jaw upon the cord while the knotter is rotating.

The wheel F is provided with a projecting flange, i, against which the flattened portion 20 i' of the knotter-pinion rests, and by which it is held during the major portion of the rotation of the wheel F. This arm or flange i is cut away over the teeth G, as shown in Fig. 1, so as to permit of the rotation of the pinion h when the teeth G come in contact therewith. The wheel F is also provided with a scroll-tooth or ridge, o, and corresponding depressions n for rotating the cord-disk two notches at each rotation of the wheel. This 25 wheel is also provided around its axis with the cam-groove K, having the form shown in Fig. 3 for operating the rocker-arm R, the cam being formed in an enlarged part, J, of the wheel F, which is partly formed in the hub F'.

On the side opposite the wheel F, I place the cam-wheel H, having the cam-groove H', for operating the knife-arm, which has a side arm, L', carrying the anti-friction roller or 40 wheel, b, at its end. While the wheel b rests against the exterior portion of the cam-wheel, no movement of the knife-arm takes place. When it enters the cam-groove H', the knife-arm is advanced so as to sever the cord and 45 returned again to position, which is accomplished by the form of the cam-groove shown in detail at Fig. 7.

By pivoting the knife-arm at a and extending its operating-arm L' over to the front side 50 of the knotter, I give the arm a stronger, slower, and easier action than has heretofore been given to devices for severing the cord, and avoid the jerking or sudden action which has heretofore taken place in severing the 55 cord and slipping the knot from the knotter-bill. The slipping of the knot from the knotter-bill is also eased by the action of the disk-frame P, hereinafter explained.

At the under or back side of the knife-arm 60 I place a projection, e, (shown in Fig. 6,) to which the spring f is applied, so as to cause this spring to partake of the swinging action of the knife-arm, and by this arrangement I give the spring a strong pressure on the pin 65 g at the proper time, and relieve the pin from the spring-pressure at the proper time in its rotation, so as to ease the movement of the

opening and closing of the jaws, and thereby improve their action.

The disk-frame P is suspended from the knotter-shaft T by the ears P', so that it can swing back and forth upon said shaft. The lower end of this frame is provided with the disk Q, which has notches on its periphery, as shown at Fig. 5, in one of which the binding-cord is laid by the needle-arm. This disk is provided with the spring or cord holder S, which is attached as shown in said Fig. 5, and which is provided at its lower end with a fork or side arms, S', which are also 80 springs. The spring S locks the cord within the disk Q, while the side arms of the spring S' press the cord against the sides of the disk and yield to any irregularities in the cord, and also adapt themselves to any variations in the size of the cord, and by their application I am enabled to use cords varying in size, and also poorer grades of cord, which are liable to vary in size or diameter at different parts of the same cord. This 85 disk-frame is advanced to the knotter, as shown in Fig. 3, or made to recede therefrom, as shown in Fig. 1, by the rocker-arm R, which is pivoted to a proper projection from the knotter-stand, and which is provided at its upper end with a side pin or roller, traversing the cam-groove, K, and at its lower end with a pin projecting into a slot in the disk-frame, as shown at Figs. 1 and 3. The disk-wheel is advanced by this arrangement 90 toward the knotter while the knot is being tied, so as to relieve the strain and also to avoid a wastage of cord, and it is then returned to the position shown in Fig. 1, while the needle-arm is back and the bundle being 95 gathered, where it is held until grasped by the knotter, so as to give a sufficient length of cord for a proper knot, and it is then advanced to ease the strain when the knot is to be tied. It is in its return position when the 100 cord is laid into the proper notch of the disk Q, and while the cord is held across the disk by the needle the wheel F is so timed that the tooth o of the wheel F passes between two of the side teeth of the disk Q, and turns 105 the disk to the extent of two notches, which carries the cord over between the disk and the spring S' and locks it there for the return movement of the needle. The general 110 operation of the knotter is similar to that shown in United States Letters Patent No. 333,922, so that it does not require a particular description, and by the special arrangements of the parts pointed out as new the particular action of the knotter is simplified and 115 improved and its action eased, so that it has no sudden or jerking movement, and for this reason I am enabled to use inferior grades of 120 cord.

What I claim as new, and desire to secure 130 by Letters Patent, is—

1. The depressed knife-arm extending through the breast-plate, in combination with the breast-plate, constructed as described, and

the knotter O brought down to the breast-plate, whereby the knot is formed nearer to the bundle and the cord shortened, substantially as described.

5 2. The combination of the knotter-frame, the spring f, the swinging knife-arm L, and the knotter O, whereby an intermitting pressure is applied to the pin g of the knotter, substantially as specified.

10 3. The knife-arm L, having notch c, for passage of the knotter-bill, side operating-

arm L', projections or plates M N, and knife l, in combination with the cam H H', knotter-bill, and knotter-stand D, substantially as shown and described.

15 4. The arm L, having the notch or opening c, in combination with the knotter-bill, substantially as specified.

CHRISTIAN H. SALZMAN.
